UNITED STATES PATENT OFFICE.

PAUL FREDERICK RICHTER, OF NEWARK, NEW JERSEY.

CHORD-CONTROLLING MEANS FOR INSTRUMENTS OF THE LUTE TYPE.

Application filed September 17, 1926. Serial No. 136,083.

This invention relates to appliances for facilitating the production of harmonious tones from stringed musical instruments of the lute class in which the strings are caused to vibrate by plucking, such as banjos, guitars, ukuleles, etc.

It is well known that instruments of the type mentioned are composed of a hollow body, an elongated neck and a head having means for adjusting the tension of each individual string.

The strings are attached to the body, at a point opposite the neck, to extend over a bridge resting on the body, thence over the neck to tuning keys carried by the head and are vibrated by picking strokes of a plectrum or by a player's finger direct.

The several strings are tuned to produce definite tones which are modified by being depressed to make contact with slightly raised transverse ridges or frets on the neck whereby differently pitched tones are produced.

In order to play such instruments satisfactorily it is required that the fingering, that is a suitable depression of the individual strings upon the proper fret, be accurately accomplished as otherwise discordances occur destroying the harmonious effect of the music and ideal fingering is an art difficult to acquire.

It is therefore one of the objects of the present invention to provide a device attachable to or to be a part of stringed instruments or as a component part thereof as will render the same readily played and pleasing musical effects produced by a player having little or no previous knowledge of the art.

A further feature is in the provision of a device, small, compact and inconspicuous, that may be readily applied to such musical instrument, with relation to the frets thereon, over and parallel with the strings, and which, in conjunction with a selective key, will control the strings, causing them to produce any definite chords upon being plucked.

These several objects are attained by the novel construction and combination of parts constituting the invention as hereinafter described and illustrated in the accompanying drawing, forming a material part of this disclosure, and in which:

Figure 1 is a top plan view of the assembled device.

Figure 2 is a bottom plan view of one of the string engaging bar elements in detail.

Figure 3 is a fragmentary sectional view of one of the bars showing its spring controls at the end thereof.

Figure 4 is a transverse sectional view of a bar, drawn to an enlarged scale and showing a fragment of its actuating key, the broken lines indicating the parts after actuation.

Figure 5 is a perspective view of an actuating key in detail.

Figure 6 is a fragmentary perspective view of a bar as engaged by an actuating key.

Figures 7, 8 and 9 are partial views of a conventional stringed instrument neck, together with frets and strings, illustrating the application of the positioning means whereby the strings are selectively depressed.

Figures 10, 11 and 12 are transverse sectional views of the same showing the operation of the bars and positioning elements as depressed by selective keys.

The device consists of an open rectangular frame 15 secured by any preferred means on the neck X of a stringed instrument, over and parallel with the strings four being shown, respectively 1, 2, 3 and 4.

The frame 15 contains in its short opposite sides, vertical slots 16 in which are slidably received the reduced circular ends or pintles 17 of a plurality of positioning bars 18, 19, 20 and 21 having triangular faces 18^a, 18^b and 18^c, etc., each provided with string stops 18^{a'}, 18^{b'} and 18^{c'} arranged at intervals along their lengths corresponding to the mid distance between frets E, F, G and H on the neck X.

Fixed on the pintles 17 at one end only of the bars are rectangular blocks 22 adapted to seat against the leaves 23 of flat springs 24 secured adjacent the slots 16 by pads 25 and so cause the bars to return to their normal position after they have been operated.

The pintles 17 at each end of the bars are normally held at the upper ends of the slots 16 by compression springs 26 disposed in the slots 16 and the bars are normally held in the position shown in Figure 4 by reason of the spring 24 as indicated in Figure 3 or other analogous flexible retaining means.

The string stops 18^{a'}, 18^{b'}, 18^{c'}, etc. are so arranged that each one can only contact the particular string over which the bars are

positioned, at a point intermediate specific frets as best seen in Figures 7 to 12.

These several bars are rockable on their pintles to selectively direct any of the string stops borne by them downwardly between any adjacent frets, and are also moved down in the frame by a series of control keys, one for each chord to be produced thereby aligning the string stop or stops to engage with the desired string or strings.

These keys 27 consist of flat plates, their length being equivalent to the width of the frame 15 to enter and be guided by it and present on their lower edges permutative features whereby the several bars may be pressed directly straight down and prevented from turning, as by triangular notches 28 engaging the angled edge of a bar opposed to the flat face 18^b, etc., or cause the bar to rotate into a position to present either of its other faces 18^a or 18^c, as by projections 29 on the edge of the key.

As an example, let it be required to dispose the strings as in Figures 7 and 10, in which strings 2 and 4 remain normal and strings 1 and 3 are to be modified.

This is accomplished by depressing a specific key 27 downwardly in the frame 15. Thus the bar 18 will be rotated to bring the stop 18^a into contact with string 1 between the frets E and F.

Simultaneously the bar 20 is pressed straight downwardly bringing the stop 20^b into contact with the string 3 between the frets F and G.

The key 27 as used in Figures 8 and 11 causes the bar 20 only to contact the string 3 between frets F and G.

However in Figures 9 and 12 the key 27 as shown therein, causes the bar 18 to rotate clockwise bringing the stop 18^a into engagement with the string 1 between frets G and H, while the bar 19 is rotated counter clockwise to cause the stop 19^a to engage the string 2 between frets E and F and the bars 20 and 21 are depressed straight downwardly to bring the stops 20^b and 21^b into contact with the strings 3 and 4 respectively between the frets F and G.

Thus it may be seen that the device as above described enables an operator to play a stringed instrument without any previous knowledge of string fingering.

It may also be seen that a small, inconspicuous and compact device has been disclosed for the purposes mentioned.

Although I have described my improvements with considerable detail and with respect to certain particular forms of my invention, I do not desire to be limited to such details since many changes and modifications may well be made without departing from the spirit and scope of my invention in its broadest aspect.

Having thus described my invention, what

I claim as new and desire to secure by Letters Patent, is:—

1. In combination with a musical instrument having a neck provided with frets over which extend tuned strings, of a series of bars pivotally secured on said neck longitudinally one over each string, a series of string stops corresponding to said frets fixed semi-spirally on each bar, means for depressing one or more of said bars, and means combined therewith to partially rotate one or more bars to cause said stops to engage the strings adjacent certain of the frets predeterminedly. 75

2. In combination with a musical instrument provided with frets over which are a series of tuned strings to be plucked, of a bar pivotally mounted on said instrument over each string, a series of string stops fixed in spaced relation to extend radially at different angles from said bar, means for rotating said bars to bring any stop thereon into predetermined position relative to the frets, means combined with the rotating means for selectively depressing said bars, 85 and means for restoring said bars to their normal position upon release from said depressing means. 90

3. In combination with a musical instrument provided with frets over which extend tuned strings, of a vertically slotted frame fixed on said instrument over the strings, bars having pintles pivotally and slidably mounted in the slots of said frame in register with the strings, said bars having angular faces, resilient means to raise said bars, other resilient means to return said bars to their normal position after actuation, a string stop set in each of the lower faces of said bars, said stops being spaced in conformity with said frets, and a plurality of depressible control keys guided by said frame and having permutative edges each representing a chord, said keys being used selectively to rotate and depress said bars in a predetermined manner. 100 105 110

4. In combination with chord controlling bars, a key to actuate said bars, said key having a plurality of predetermined notches and projections to cause said bars to move 115 in a downward, clockwise or counter clockwise direction.

5. In combination with a musical instrument of the lute type, a series of rockable bars, string stops on said bars, and keys to 120 operate said rockable bars whereby the string stops may be registered with the strings of the instrument either singly or in combination.

6. In combination with a musical instrument of the lute type, a series of depressible rockably mounted bars each containing a plurality of string stops, and keys to actuate said bars, each of said keys containing chord formative combinations. 125 130

7. In combination with a musical instrument of the lute type, a key controlled series of rockable bars, each containing string stops alinable with the strings of the instrument ⁵ to form chord positions thereof when said key is depressed.

8. In combination with a musical instrument of the lute type, a series of rockable

bars containing position string stops, said stops being alinable either singly or in series ¹⁰ to form chords of the instrument strings, and a key containing chord combinations to depress said bars.

This specification signed this sixteenth day of September, 1926.

PAUL FREDERICK RICHTER.
